UNITED STATES PATENT OFFICE

JOSEPH J. MARIOTTI, OF CHICAGO, ILLINOIS, ASSIGNOR TO DAPRATO STATUARY COMPANY, OF CHICAGO, ILLINOIS, A CORPORATION OF ILLINOIS

DOOR OPERATING MECHANISM

Application filed May 1, 1931. Serial No. 534,176.

My invention relates to safes or vaults and particularly to that type of safe or vault which may be used as a tabernacle.

Vaults of this type are usually comparatively small in size and installed in full public view and therefore must be strongly and heavily constructed without being cumbersome in order to prevent unwarranted entry thereinto yet permit access by authorized persons and present a pleasing appearance.

It is the purpose of my invention to provide a safe particularly suitable as a tabernacle which is strongly constructed, substantially burglar proof and yet readily accessible to authorized entry.

In accordance with my invention I provide a vault preferably a double walled vault having sliding doors which are automatically, simultaneously operable for closing the entrance into the vault. The doors and vault are so constructed that there is no opening through the bottom of the vault at the bottom of the doors through which articles may be dropped when removing them from or placing them in the vault.

In the illustrated embodiment of my invention I have shown a vault having a pair of doors which meet at the center and swing away from each other into the space between the two walls of the vault leaving a clear and entirely free opening into the vault. The doors are provided with novel interconnections by means of which movement of one door will automatically impart movement to the other door whereby it is necessary to manually open only one door.

A more complete understanding of my invention will be had from the following description taken in connection with the drawings in which:

Fig. 1 is a plan view of the tabernacle with the top dome cover removed.

Fig. 2 is a vertical section on line 2—2 of Fig. 1.

Fig. 3 is a transverse horizontal section on line 3—3 of Fig. 2.

Fig. 4 is a fragmentary section on line 4—4 of Fig. 1.

Fig. 5 is a diagrammatic detail of an upper and lower arm supporting one door member.

Fig. 6 is a front elevation of one door member and associated parts.

In the illustrated embodiment of my invention I have shown a double walled vault which in effect is one walled vault within another, the door and door operating mechanism being secured to and supported from the inner vault. It will be manifest as the description proceeds that the door operating mechanism may be applied to other vaults.

The inner vault or safe chamber is constructed of a single sheet of metal 1 preferably sheet steel or some other suitable material and curved into a partial cylinder, the vertical terminating ends of which are spaced to provide an entry or opening into the vault. For appearance or additional strength the chamber may be lined with a single sheet of metal 2 such as bronze the ends of the two sheets 1 and 2 being finished and bound together by channel shaped strips 3. The upper edge of sheet 1 is secured to an angle ring 4 to which is attached a top plate 6. The lower edge of sheet 1 is secured to a similar angle ring 7 to which is attached a bottom plate 8. A vault chamber is thus provided and enclosed by a cylindrical wall 1 top plate 6 and bottom plate 8.

The top plate 6 and the bottom plate 8 carry spacers 9 which support the outer shell or casing. For this purpose an upper ring 11 and a lower ring 12 are secured to the spacers by screws or the like. An angular rim 13 is secured to the upper ring 11 and a similar angular rim 14 is secured to the lower ring 12. The outer shell 16, trimming members 17 and base 18 are all secured either directly or indirectly to rim 14. The outer shell 16 is provided with an opening in alignment with the opening through the inner shell to permit access into the vault chamber. The space beneath the door opening and between plate 8 and the base 18 is closed by an arcuate front plate 19.

The upper end of the outer shell is closed by a dome-like structure 20 and suitable trimming members 21 and 22 all carried by the angular rim 13.

In order to close the door opening or entry through the two shells, I provide a pair of

swinging doors 23 and 24 secured to door carrier plates 26 and 27 respectively. The doors and plates are arcuate and arranged to slide between the inner and outer shells. The carriers 26 and 27 extend above and below end plates 6 and 8. Carrier plate 26 is secured to and is supported by an upper arm 28 and a lower arm 29. Carrier plate 27 is secured to and carried by an upper arm 31 similar to 10 arm 28 and a lower arm 32 similar to arm 29. The inner ends of upper door arms 28 and 31 are provided with circular bearing receiving bosses and are pivoted upon a common bearing post 33 carried by and projecting upwardly 15 from top plate 6. Suitable bearings 34 are interposed around and between the arms. Lower arms 29 and 32 are similarly pivoted to a common post 36 rigidly secured to bottom plate 8, suitable bearings 37 being applied 20 between the post and the arms.

The carrier plates are provided with main portions which extend above and below the end plates of the inner vault chamber and join the upper and lower arms and forward 25 portions to which the doors are attached, the forward portions are cut away and stop at substantially the level of the upper and lower plates. This construction permits of a substantially flush connection between the 30 lower plate 8 and the arcuate front plate 19. In order to provide a flush or closed entrance into the vault a flat plate 38 is secured to the curved front plate 19 in a horizontal position to extend across the opening into the vault 35 and completely close the space between plate 19 and the front edge of the lower end plate 8. This construction will permit the door plates and the doors to be rigidly carried by the two arms the latter being connected by 40 the plates and yet the door may extend in front of the entry and close the entry into the vault chamber without the necessity of having an opening through which the lower ends of the doors may slide.

In order that the two doors will open simultaneously and automatically, that is, in order that movement of one door will impart movement to both doors, the upper arms 28 and 31 are provided with two laterally projecting 50 lugs 39 and 41 respectively at a point intermediate their terminating ends to which one end of links 42 and 43 are pivoted. The other ends of links 42 and 43 are connected together by a pivot pin 44 at a point behind the door 55 arm pivot post 33. Pivot pin 44 carries a roller 46 which tracks between a pair of angle guide rails 47 and 48 secured to end plate 6. The movement of pin 44 is accordingly restricted to a radial movement toward and 60 from pin 33. The outer ends of rails 47 and 48 are bent inwardly to engage a stop block 49 which will limit the outer movement of roller 46.

It follows from the above that if either door 65 23 or 24 and its corresponding arm 28 or 31

is moved toward open or closed position about pivot pin 33, the opposite arm and its door will be moved in a similar direction. Assuming the doors to be closed, if door 23 is opened moving arm 28 in a clockwise direction about post 33, link 42 will urge link 44 away from post 33 and will thereby tend to move arm 31 in a counterclockwise direction through a pull on link 43. The reverse movements will be apparent from the foregoing description as 70 it will be apparent that either door may be manually operated resulting in the automatic simultaneous movement of the other door. 75

From the above description it can be seen that there has been provided a substantially 80 burglar proof vault comprising an inner vault chamber within an outer chamber having a pair of doors which are readily and easily operable, it being necessary only to operate one door. The construction also permits of a threshold plate to provide a smooth 85 enclosed entrance into the vault thus avoiding the possibility of snaring articles as they are placed in or withdrawn from the vault.

It is understood of course that many 90 changes may be made in the details of construction without departing from the spirit and scope of the invention as defined in the claims appended hereto.

I claim:

1. In combination a pair of vertical doors having horizontal supporting arms extending radially therefrom and pivoted at their inner ends about a common fixed vertical pivot whereby said doors will swing bodily toward 100 and from each other in an arcuate path and connections between said doors for causing automatic simultaneous operation of said doors, said connections comprising a pair of links pivotally connected together at one end, 105 means for guiding said connected ends for movement in a direction laterally of the door pivot, one of said links being pivoted to each of said arms at a point between the door carried thereby and said door pivot. 110

2. In combination a pair of vertical doors having horizontal supporting arms extending radially therefrom and pivoted at their inner ends about a common fixed vertical pivot whereby said doors will swing bodily 115 toward and from each other in an arcuate path, connections between said doors for causing automatic simultaneous operation of said doors, said connections comprising a pair of links pivotally connected together at one end, 120 one of said links being pivoted to each of said arms at a point between the door carried thereby and said door pivot, and a track extending radially from said door pivot and engaging said pivoted ends of said links to 125 guide said ends in a direction radially of said door pivot.

3. In combination, a pair of vertical doors having horizontal supporting arms extending radially therefrom and pivoted at their inner 130

ends about a common fixed vertical pivot whereby said doors will swing bodily toward and from each other in an arcuate path, connections between said doors causing automatic simultaneous operation of said doors, said connections comprising a pair of links pivotally connected together at one end, a roller secured to said end, one of said links being pivoted to each of said arms at a point between the door carried thereby and said door pivot, and a track extending radially from said door pivot and engaging said roller to guide said roller and connected ends in a direction radially of the door pivot.

15 In witness of the foregoing I affix my signature.

JOSEPH J. MARIOTTI.
